Assistant Examiner — Jeremy S. Swartz

(57) **CLAIM**

The ornamental design for combination wall mounted key holder, substantially as shown and described.

DESCRIPTION

FIG. 1 is a perspective view of its front;

FIG. 2 is a perspective view of its back;

FIG. 3 is a plan view of its front;

FIG. 4 is a plan view of its back;

FIG. 5 is the plan view on the left;

FIG. 6 is the plan view on the right;

FIG. 7 is a plan view of its top surface; and,

FIG. 8 is a plan view of its bottom surface.

The broken lines in the drawings illustrate the portions of the wall mounted key holder, which form no part of the claimed design.

1 Claim, 8 Drawing Sheets
